UNITED STATES PATENT OFFICE.

GEORGE CLEMENTS, OF CHICAGO, ILLINOIS, ASSIGNOR TO CLEMENTS MANUFACTURING COMPANY, OF CHICAGO, ILLINOIS, A CORPORATION OF ILLINOIS.

DESIGN FOR A CLIP.

44,433.

Specification for Design.

Patented Aug. 5, 1913.

Application filed March 24, 1913. Serial No. 756,596. Term of patent 14 years.

To all whom it may concern:

Be it known that I, GEORGE CLEMENTS, a citizen of the United States, residing at Chicago, in the county of Cook and State of Illinois, have invented a new, original, and ornamental Design for a Clip, of which the following is a specification, reference being had to the accompanying drawing, forming part thereof.

Figure 1 is a side elevation of a clip showing my new design; Fig. 2 is a plan view of the same.

I claim:

The ornamental design for a clip as shown.

GEORGE CLEMENTS.

Witnesses:

MINNIE M. LINDENAU,
MINNIE SUNDFOR.
